UNITED STATES PATENT OFFICE.

ALLEN J. WRIGHT, OF CLEVELAND, OHIO.

FLOAT.

SPECIFICATION forming part of Letters Patent No. 340,534, dated April 20, 1886.

Application filed February 4, 1886. Serial No. 190,870. (No model.)

To all whom it may concern:

Be it known that I, ALLEN J. WRIGHT, of Cleveland, in the county of Cuyahoga and State of Ohio, have invented certain new and useful 5 Improvements in Floats; and I do hereby declare the following to be a full, clear, and exact description of the invention, such as will enable others skilled in the art to which it pertains to make and use the same.

10 My invention relates to improvements in floats; and it consists in certain features of construction and in combination of parts hereinafter described, and pointed out in the claims.

Heretofore floats have usually been spun in halves, and made the one part to slip a short 15 distance into the other part, or have been made with an interlocking joint, the one part being spun over an outwardly-projecting flange of the other part. In either case the 20 seam was soldered to make a tight joint. For ordinary floats the metal is necessarily thin, and is quickly heated through in soldering, by reason of which the air inside of the float is expanded, causing an outward pressure that 25 is likely to make fine blow-holes in the solder. These blow-holes are often so small that they are not visible, and the float when supposed to be perfect may, in fact, be quite imperfect, and if placed, for instance, in a steam-boiler 30 to operate an automatic feed-water regulator, or if placed in an alarm-gage, such imperfect float will after a time become filled with water and cease to be a float, and serious damage may accrue therefrom. Solder for such pur- 35 poses is at best unreliable, and is likely to be corroded by substances in the water, so that the float in consequence thereof eventually becomes worthless. In view of these diffi- 40 culties I have devised a float in which no solder need be used; but in place thereof the two parts of the float are pressed over an inside band, so that a tight joint is made, the inside band of course serving to hold the two parts of the float together and to strengthen the float.

45 In the accompanying drawings, Figure 1 is a side elevation of a float embodying my invention, a portion of the shell thereof being broken away to show the internal construction and the manner of making the joint. Fig. 2 50 is an elevation of a float, showing a different form, and showing, also, an interlocking of the parts, in addition to the joint shown in

Fig. 1. Fig. 3 is a detail showing another modification of the interlocking parts.

The form of the float is not essential, the 55 one shown in Fig. 1 being spherical, that shown in Fig. 2 being cylindrical with spherical ends. These or other forms may be used at pleasure or adapted according to circumstances.

A and A' represent the two parts of the shell. 60

B is an internal band, and may have one or more inside annular ribs or flanges, b, for stiffening the band. The shells A and A' are forced on over the band B, and are offset, respectively, at a and a', so that the internal shoulders at 65 these points, by engaging the edges of the band, cause the abutting edges of the shell to meet approximately at the center of the band, as shown in Fig. 1. If the shells while expanded by heat—for instance, by dipping them in hot 70 water—are forced over the band B, the shrinkage of the shells upon the bands will insure a tight joint sufficient for ordinary purposes.

For notwithstanding, for instance, a heavy 75 steam-pressure, if it is desired to still further secure the parts by interlocking them, it may be done in either of the following manners, to wit: First, where the shell A is still further offset at a', so as to pass over the large part of the shell A', and after the parts are in position, 80 the extreme edge of the shell A is spun or compressed over the external shoulder at a' of the shell A', or, as shown in Fig. 3, the shell A' may have an annular flange, a³, spun outward, while the part A has a similar but 85 broader flange, a⁴, (see dotted lines in Fig. 3,) that is spun over the flange a³, as shown. Either of these two forms of interlocking the parts will be found effective.

What I claim is—

1. A float consisting, essentially, of a shell made in two parts and joined together by means of an internal band arranged to overlap the joint, the two parts of the shell being preferably forced and shrunk upon the band, 95 substantially as set forth.

2. In a float, the combination, with a shell made in two parts, of an internal band arranged to span the external joint, said band having one or more inside ribs or flanges, sub- 100 stantially as set forth.

3. In a float, the combination, with a shell made in two parts, of an internal band for uniting the two parts of the shell, said shell

having offsets or shoulders for engaging the edges of the internal band, substantially as set forth.

4. In a float, the combination, with a shell
5 made in two parts that are joined by an internal band, of a lock-joint formed by spinning or compressing the edge of one part of the shell over a shoulder, flange, or projection of the other part of the shell, substantially as set forth.

In testimony whereof I sign this specification, in the presence of two witnesses, this 29th day of January, 1886.

ALLEN J. WRIGHT.
